UNITED STATES PATENT OFFICE.

EVAN WALTER DAVIES, OF GLAMORGANSHIRE, WALES.

APPARATUS FOR MANIPULATING METAL INGOTS IN ROLLING-MILLS.

1,312,104.

Specification of Letters Patent.

Patented Aug. 5, 1919.

Application filed June 22, 1915. Serial No. 35,668.

To all whom it may concern:

Be it known that I, EVAN WALTER DAVIES, a subject of the King of Great Britain, residing at Glamorganshire, Wales, have invented new and useful Improvements in Apparatus for Manipulating Metal Ingots in Rolling-Mills, of which the following is a specification.

This invention relates to apparatus for manipulating metal ingots in rolling mills and refers more particularly to appliances adapted to work in conjunction with rollers for conveying ingots, rails and the like generally used in feeding the various kinds of rolling mills at metallurgical works, such appliances being more especially designed for turning the ingots or other articles under treatment.

The apparatus is of the type comprising devices adapted to clutch the ingot or other article under treatment automatically, to turn it through a suitable angle about its longitudinal axis, and if desired to move it transversely to a convenient position on the conveying rollers, for direct transmission to any desired forming groove in the roller mill, such clutching devices being reciprocated simultaneously or independently in either direction across the ingot or other article under treatment conveying plane by means of mechanism controlled by the operator.

My invention consists of an improved construction of apparatus of the beforementioned description, constituting a self-contained and direct acting combination of appliances for the more effective handling of ingots or other articles under treatment throughout their development to finished articles, the apparatus being moreover so constructed as to automatically adapt itself to the varying size of any ingot or other article under treatment when between its clutches without necessitating special care or judgment on the part of the controlling operator.

By suitably operating the foregoing apparatus an ingot or the like can be clutched between the clutching devices, turned through the desired angle and if desired transported as required.

And in order that my said invention may be better understood, I will now proceed to describe the same with reference to the drawing accompanying this specification, in

55 which:—

Figure 1 is a front elevation of the appa-

ratus with the conveying rollers and girder at the front removed, the parts of the apparatus being shown in the initial position preparatory to the turning of the article 60 under treatment, which in the drawing is represented as a rail.

Figs. 2 to 5 are diagrammatic views illustrating successive stages in the operation of the mechanism and in the turning of the 65 work piece.

Fig. 6 is a similar view to Fig. 1 showing the parts of the apparatus in the final position which they will assume after the work 70 piece has been turned.

The mechanism as shown in the figures is arranged parallel to the rollers of the mill which it is intended to serve.

The same numerals of reference are employed to denote the same parts in the 75 views:—

1 are end standards or supports, to the front and back of which are connected girders 2, only the back girders, as previously stated, being shown in the drawing. 3 are 80 rollers for conveying the work piece, only one of which can be seen on the drawing, it being understood that there are others arranged in the same plane behind this roller; and in a complete apparatus others 85 arranged in the front. 4 shows the work piece, in this case a rail to be operated upon, in end view. 5 is a piston rod, to which is connected a cross head 6. This piston rod works in a suitable renewable 90 bearing carried by the standard 1. Coming on either side of the cross head is a plate 7 carrying rollers 8 which roll upon the surface of the girders 2. 9 is a guide plate mounted at the bottom of the cross head 6 95 and coming beneath the girders 2. The pivot 10 of the forward rollers is extended right through and has mounted thereon the holder 11 of the receiving clutch 12. This holder 11 is fork-shaped at the upper part 100 and provided with a slot on each side into which the ends of the pin 13 of the receiving clutch are mounted. 14 is a combined stop and binder for the clutch plate 12. The lower part of the receiving clutch holder is 105 shaped as shown and is provided with a balancing portion 15. At the other side of the apparatus is another piston rod 16, which works in a suitable renewable bearing and is connected to a cross head 17, so as to 110 run upon the girders 2 in a similar manner to the cross head 6. The cross head 17 has

hinged into a gap in the top thereof a two-armed lever, the shorter arm 18 of which has pivoted thereto a pair of links 19 (only one being shown in the drawing as they come directly in front of one another) the other ends of which links are pivoted to a sliding carriage 20. The sliding carriage 20 is provided with running wheels toward the top and a guide plate or slide at the bottom, so as to work upon the girders 2 in a similar manner to the cross heads 6 and 17. The upper part of the carriage 20 is provided with a pin or pivot 21 the ends of which take into quadrant shaped slots 22 in quadrant tumblers 23, it being understood that one quadrant tumbler comes on either side of the carriage. 24 is a pivot on each quadrant tumbler 23, which has mounted thereon and so as to come on the inside of the tumblers a link 25, formed with a large quadrant slot 26. 27 is the turning clutch, shaped as shown and provided with a projecting pin 28 on each side thereof, which takes into the quadrant-shaped slots 26 of the links 25. 29 is a link or arm pivoted at one end to the longer arm 30 of the two armed lever carried by the cross head 17, and at the other end to the pivot 28 of the turning clutch 27. 31 are faces cut on the interior and at the rear of the turning clutch 27, forming bearing faces for the link or arm 29. 32 is a distance piece coming between the quadrantal links 25, and 33 is an inclined resting shoulder on the cross head 6 for the clutch holder 11 (see especially Fig. 6.)

The wear on the guides and wheels may be taken up by means of adjusting screws 34, one only of which is shown to the left-hand side of Fig. 1.

In the operation of the device, certain combined actions of the beforementioned parts take place, which enable the work piece to be turned and if desired transported.

When the contact face of the turning clutch 27 comes into contact with the work piece 4, and the lower portion of the receiving clutch holder 11 is engaged by the surfaces of the quadrant tumblers 23, resistance is put upon the movement of the carriage 20. As the movement is continued and the cross-heads approach each other, the tumblers 23, carrying the link 25, are rocked to effect initial engagement between the clutch 12 and the work-piece 4, which rocking action is due to the fact that the pivot 10 is lower than the pivot 21 carried by the carriage 20 upon which pivot the tumblers 23 and that the said tumblers are engaged by the holder 11 as seen in Fig. 2, the slots 22 of the tumblers, which receive the pivot 21, allowing of the requisite movement of said tumblers. This action, however, causes a certain amount of resistance

to the movement of the carriage 20. This is transmitted to the links 19 operating the lever 30 and causing the pin 28 to rock up the link 25, said pin 28 and the slot 26 of the latter allowing said link to conform to the movement indicated. The pivot 24 of this link is already being moved upward as it is pivoted in the rising tumblers 23. It will of course be understood that the work piece 4 is in contact with the clutch faces and from reference to Figs. 2 and 3 the manner in which it is caught up by the clutches will be readily seen. The positions of the operating parts in the successive diagrams will be readily followed from the time that the work piece is in its initial position at Fig. 1 until it is turned over as shown at Fig. 6.

The slot 22 allows the upward movement of the tumblers to take place as will be easily understood.

When the apparatus is in the position shown at Fig. 6, both cross heads can, if desired, be worked simultaneously to carry the work piece within pre-arranged limits to a place opposite any desired forming grooves in the mill rollers.

The foregoing action is rendered possible by the peculiar construction of the parts, especially the arrangement of the turning clutch 27 and the method in which its position is controlled by the quadrant slots 26 of the quadrant links 25, which, as before stated, are in turn also under the influence of the tumblers 23 mounted upon the sliding carriage 20 by slots 22.

Attention is particularly directed to the fact that the pivot 21 of the tumblers 23 is at a higher level than the pivot 10 of the receiving clutch holder 11. This arrangement makes it possible for the quadrant tumblers 23 to engage with the receiving clutch holder 11, and when this is caused to turn back the quadrant tumblers 23 turn over with it, the two parts remaining at about right angles to each other.

It should be observed that the holders, arms and other intervening parts between the clutching members of the apparatus and the cross heads are assembled in what may be described as a non-rigid or flexible relationship with each other when in use, thus enabling the ingot to yield to the pull of the mill rollers at the moment they commence to draw it into the forming grooves.

The particular details of the apparatus may be varied within the scope of the appended claims without departing from the principle of the invention.

What I claim as my invention and desire to secure by Letters Patent of the United States of America is:—

1. Apparatus of the type described, including sliding members, operating means for said sliding members, a clutch having

pivotal connection with one of said sliding members, a two armed lever having arms of unequal lengths mounted upon the second sliding member, a carriage linked to the 5 shorter arm of said lever, quadrant-shaped tumblers having pin-and-quadrant-shaped-slotted connection with said carriage, a second clutch linked to the longer arm of said lever, said tumblers having pivotal-and-quadrant-shaped-slotted connection through 10 the link 25, its slot 26, and pivot 28 with said second clutch.

2. Apparatus of the type described, including cross-heads, girders and conveying 15 rollers, means for reciprocating said cross-heads between said girders and parallel to the conveying rollers, a clutch pivoted to one of said cross-heads, a two-armed lever having arms of unequal lengths pivoted at 20 the upper portion of the second cross-head, a carriage linked to the shorter arm of said lever, quadrant-shaped tumblers having pin- and - quadrant - shaped slotted connection through the pin 21, and slots 22 with said 25 carriage, a second clutch linked to the longer arm of said lever, said tumblers having pivotal - and - quadrant - shaped slotted connection through the link 25, its slot 26, and the pivot 28 with said second clutch.

3. In apparatus of the type described, the 30 combination of slidable members adapted to be moved toward and away from each other, an intermediary carriage, one of said slidable or movable members being provided with a tumbler provided with a pivoted toothed or serrated clutch, the other 35 slidable member being provided with a

lever one arm of which is linked to said carriage, said carriage being provided with a pivoted tumbler provided with a slotted pivoted link and a second clutch, the other arm of said lever having a pivotal link-connection with the latter clutch, the pivot of said connection working in the slot of said link, whereby as said slidable members are moved 40 to a given position said carriage will so to a given position said carriage will so actuate said lever as to cause the movement of one tumbler to position one clutch at an elevation and into engagement with one edge of the ingot and tip the latter edge- 45 50 wise while said tumbler will be caused to engage and depress the other tumbler with the other clutch causing the latter clutch to receive and hold the opposite edge of the ingot for the requisite manipulation or 55 presentation of the ingot at different angles in its treatment.

4. Apparatus of the type described, including slidable members, tumblers carried by said slidable members, clutches pivotally 60 carried by said tumblers, a carriage controlled by one of said slidable members, means controlled by said carriage for actuating one of said clutches, one of said tumblers being adapted to actuate the other 65 tumbler, whereby said clutches are actuated so as to serve conjointly for engaging and manipulating the object or work.

In testimony whereof I have hereunto subscribed my name.

EVAN WALTER DAVIES.
